a. Ponack

Attorney

UNITED STATES PATENT OFFICE

ISADORE FRIEDMAN, OF ROXBURY, MASSACHUSETTS

COMBINED BEACON AND LANTERN

Application filed February 12, 1930. Serial No. 427,811.

The present invention relates to the art of electrically illuminated lanterns, and deals more particularly with a combined lantern and beacon especially adapted for the illumination of gasoline filling stations, service stations and the like.

Among the objects of the present invention are

(a) To provide a novel combined lantern and beacon which shall possess the dual functions of projecting a concentrated beam of light upwardly into the air to attract the attention of persons at great distances from the device, and of simultaneously adequately illuminating its immediate surroundings. This is particularly advantageous when the invention is used in connection with gasoline filling stations and the like. Each of a system of such stations could be provided with a plurality of the lanterns. The peculiar effect, visible by motorists perhaps miles away, which would be created by the plurality of upstanding beams of light would then be associated by the motorists with the particular system of stations and their gasoline. A motorist, whose supply of gas was running low, seeing the lights above described could then wait until he reached the system station, and replenish his supply, instead of having to stop at a small country station selling perhaps an inferior quality of gas.

(b) To provide a novel combined beacon and lantern in which the reflector member shall be adequately protected against the elements.

(c) To provide a combined beacon and lantern which shall be artistic in appearance and rugged in its character, but shall be comparatively inexpensive to construct.

These and other objects, which will be apparent to those skilled in the art to which the present invention pertains from a perusal of the detailed description below, are attained by the embodiment of the invention herein-after disclosed, consisting of the construction and novel combination and arrangement of parts fully described below, illustrated in the accompanying sheet of drawings and pointed out in the claims hereunto appended.

In the drawings:

Figure 1 is a view, partly in section and partly in elevation, of the present invention assembled in operative position; and

Figure 2 is a half view, taken along line 2-2 of Figure 1.

In the drawings, the reference numeral 1 designates the main lantern housing as a whole. This housing is made up of a base portion 2, which may be constructed of any desired material but which is preferably made of cast iron. This base portion is adapted to act as a cradle support for the reflector unit, as will be explained in greater detail below.

Mounted upon the base portion 2 is a metallic framework made up of a plurality of heavy copper or cast iron members 3, which are securely welded or otherwise held together. The upper members 3 are inwardly offset as shown with respect to the lower members 3, and the two sets of framework thus formed are joined together by beveled portions 4. The top of the structure is formed by the beveled members 5. Centrally of the top thereof, the lantern is provided with a circular opening. At the boundary of the said opening the members 5 are formed with an annular seat 6.

The annular seat 6 provides a support for the upper or cover lens 7. This lens rests upon the rubber gasket 8 placed in the annular seat 6, and is securely held in place by the retaining ring 9. The cover lens 7 is preferably a round, molded, heat-resisting clear glass lens, and by virtue of the method in which it is positioned in the top of the lantern, it prevents the penetration into the body of the latter through its top of any undesirable foreign matter, such as rain, snow, etc.

Positioned in the openings of the framework formed by the members 3 are the glass panels 10. These are preferably made of flashed white opal glass, and because of the preferred octagonal construction of the framework shown, there are sixteen of such glass panels. In order to provide easy access into the interior of the lantern, one or more of such panels may be hinged in any desirable manner (not shown).

Supported in the base portion 2 in any desired manner is the brass reflector casing 11. The lowermost portion of the casing 11 is formed to support the lamp 12 and its socket 13, the latter being capable of adjustment to accurately focus the lamp 12.

Also supported in the casing 11 in the base 2, is the parabolic mirrored glass reflector 14. This is the means for producing a concentrated vertical beam floodlight upwardly 10 through the lantern.

Depending from the top 15 of the base 2 is a second annular seat 16, the diameter of which is much larger than the diameter of 15 the seat 6. Positioned on the seat 16 is the gasket 17. The latter forms a cushioned support for the weatherproofing lens 18, the diameter of which is substantially equal to the diameter of the reflector 14.

20 The lens 18 is securely held in place by the retaining ring 19, and is similar in character to the cover lens 7, except that it is much larger than the latter.

In operation, a floodlight lamp of sufficient 25 intensity is used. The parabolic reflector 14 projects a concentrated beam of light upwardly through the top of the lantern to act as a beacon. The flashed opal glass panels 10, which may appropriately be termed diffusing panels, act to provide general illumination on the surroundings by utilizing the light flux from the lamp which is not controlled by the reflector. In this manner there is provided a combination concentrated vertical beam floodlight (or beacon) and general illumination (or lantern) unit.

In accordance with the patent statutes, I have described the principles and construction of my combined beacon and lantern, and 40 while I have illustrated a particular formation, I desire to have it understood that the same is only illustrative of a means of carrying out my invention in one form, and that obvious changes may be made by anyone 45 skilled in the art within the scope of the following claims without departing from the spirit of my invention.

I claim:

1. A combined beacon and lantern including a housing having top and side portions, 50 a reflector unit in said housing adapted to project a concentrated beam of light upwardly through the top of the said housing, diffusing glass panels in said side portions, a 55 cover lens removably mounted in the said top, and a weatherproofing lens removably mounted adjacent to and above said reflector unit.

2. In a device of the class described, in 60 combination, a housing having a top and side portions, means in said housing for projecting a concentrated vertical beam of light upwardly through the said top, means for diffusing light through the said side portions, a 65 lens-shaped cover glass in said top, and a

weatherproofing lens in said housing adjacent to and above said projecting means.

3. A combined beacon and lantern especially adapted for the illumination of gasoline stations and the like including a housing, 70 said housing comprising a base and a metallic framework thereon, said framework having an opening in the top thereof, a reflector unit in said housing, the said base constituting a supporting means for said reflector 75 unit; said reflector unit being adapted to project a concentrated vertical beam of light upwardly through the said top, and comprising a casing, a reflector mounted in said casing, and a floodlight lamp adjustably 80 mounted in said casing; means supported in the sides of said framework comprising glass panels adapted to diffuse that portion of the light flux from said lamp which is not controlled by said reflector, whereby to provide 85 for the general illumination of the surroundings of said housing, a cover glass for said opening, and a weatherproofing lens in said housing above said reflector unit.

Signed at Cambridge, in the county of 90 Middlesex, and State of Massachusetts, this 10 day of February, 1930.
